US00D789839S

(12) **United States Design Patent** (10) **Patent No.:** **US D789,839 S**
Wolters et al. (45) **Date of Patent:** **** Jun. 20, 2017**

(54) **SCREW RETENTION FOR INTERBODY
IMPLANT**

(71) Applicant: **Life Spine, Inc.**, Huntley, IL (US)

(72) Inventors: **Madeline C. Wolters**, Carol Stream, IL (US); **James A. Rinner**, Franksville, WI (US); **Michael S. Butler**, St. Charles, IL (US); **Seetal K. Erramilli**, Naperville, IL (US)

(73) Assignee: **Life Spine, Inc.**, Huntley, IL (US)

(**) Term: **14 Years**

(21) Appl. No.: **29/521,642**

(22) Filed: **Mar. 25, 2015**

Related U.S. Application Data

(63) Continuation of application No. 13/459,137, filed on Apr. 28, 2012, now Pat. No. 9,017,412.

(57) **CLAIM**

We claim the ornamental design for a screw retention for interbody implant, as shown and described.

DESCRIPTION

FIG. 1 is a perspective view of an embodiment of the claimed design;

FIG. 2 is a bottom view thereof;

FIG. 3 is a top view thereof;

FIG. 4 is a right side view thereof, the left side view is identical to the right side view;

FIG. 5 is a front view thereof, the rear view is identical to the front view; and,

FIG. 6 is another perspective view thereof.

The broken lines are included for the purpose of illustrating unclaimed subject matter and form no part of the claimed design.

1 Claim, 4 Drawing Sheets
